UNITED STATES PATENT OFFICE

MAX A. HOHENSTEIN, OF NEW YORK, N. Y.

SLIPPER

Application filed May 12, 1928. Serial No. 277,158.

This invention relates to improvements in slippers and more particularly to improvements in washable slippers.

A particular object of the invention is 5 to provide a washable slipper having a temporary sole, the sole which lends rigidity to the slipper being removable when the slipper itself is washed.

Further objects of the invention will be 10 apparent from the specification and drawings in which

Fig. 1 is a top plan view of my improved slipper.

Fig. 2 is a side view.

15 Fig. 3 is a sectional view along the line 2-2 of Fig. 1.

Fig. 4 is a sectional view of the rear portion of the base of the slipper with the temporary sole in place.

20 Fig. 5 is a bottom plan view of the slipper with the temporary sole in place.

Fig. 6 is a plan view of the temporary sole alone.

Fig. 7 is a sectional view along the line 25 7-7 of Fig. 6.

Fig. 8 is a plan view of the pocket in the base of the slipper at the toe portion thereof.

Fig. 9 is a plan view of the base of the slipper at the heel portion thereof.

30 The upper fabric portion of the slipper is represented by A, the base by B, the binding on the upper as C, the binding on the base as D.

On the underside of the base at the toe and heel portions thereof, are positioned two pockets, the pocket at the toe portion being designated as E and at the heel portion as F. Into these pockets may be fitted the temporary sole, H, which may be made of cardboard, cork or similar rigid material, and need not be washable.

One of the advantages of putting this sole on the exterior of the slipper rather than on the inside thereof, is the fact that slippers of this character are usually employed to 45 cover feet unprotected by socks and it is therefore an advantage for the naked feet to contact with the fabric of the slipper rather than with the material of which the temporary sole may be composed, such as 50 glazed cardboard or a similar material.

My improved slipper is constructed in the following manner:

I take a washable fabric, preferably cotton, and form the top and the base thereof separately of a single piece of fabric. Two 55 operations suffice for the making of the slipper after the cutting of a pattern therefor; one operation to sew the binding for the top; the second and final operation to sew the binding for the base including the sewing of the pockets on the toe and heel portion of the slipper on the underside of the base. The operation of sewing the binding on the base includes the attachment of the upper portion of the base, as well as the attachment of the pockets on the underside 60 of the base.

I am aware that slippers have been heretofore constructed with temporary soles but believe it is new to make a slipper of the 70 construction herein shown with a sole entirely removable and functioning on the underside of the base of the slipper.

Having fully described my invention, what 75 I claim is:

A fabric slipper having separate pockets on the underside of the base and at opposite ends thereof and a rigid removable sole positioned in said pockets, the middle portion of said sole being normally exposed on the 80 underside of said slipper.

In testimony whereof I affix my signature.

MAX A. HOHENSTEIN.
